UNITED STATES PATENT OFFICE.

LEWIS T. JACK, OF MOUNT STERLING, IOWA.

GATE-HINGE.

1,146,500.

Specification of Letters Patent. Patented July 13, 1915.

Application filed March 25, 1915. Serial No. 16,849.

To all whom it may concern:

Be it known that I, LEWIS T. JACK, a citizen of the United States, residing at Mount Sterling, in the county of Van Buren and 5 State of Iowa, have invented a new and useful Gate-Hinge, of which the following is a specification.

The device forming the subject matter of 10 this application is a gate and one object of the invention is to provide a means whereby the gate will be held in a closed position even though the gate-carried latch be not engaged with the striking post, the construction being such that the gate cannot be 15 readily blown open by the wind.

Another object of the invention is to provide a device of the type above indicated, in 20 which an inclined track exercises a double function, in that it constitutes a means whereby the gate will be made to gravitate toward a closed position, and constitutes also an element with which a portion of the locking mechanism is adapted to engage.

It is within the province of the disclosure 25 to improve generally and to enhance the utility of devices of that type to which the present invention appertains.

With the above and other objects in view 30 which will appear as the description proceeds, the invention resides in the combination and arrangement of parts and in the details of construction hereinafter described and claimed, it being understood that changes in the precise embodiment of the 35 invention herein disclosed can be made within the scope of what is claimed, without departing from the spirit of the invention.

In the accompanying drawing:—Figure 1 shows the invention in side elevation, parts 40 being broken away; Fig. 2 is a top plan, parts being broken away and sectioned; Fig. 3 is a section on the line 3—3 of Fig. 1; Fig. 4 is a fragmental side elevation showing a modified form of the invention.

In carrying out the present invention 45 there is provided a gate embodying a frame, the frame including a top bar 1, a bottom bar 2 and end bars 3 and 4. The gate frame thus described of course embodies a filler 5 of any desired sort, the filler being broken away in order that the essential features

of the invention may not be obscured. The top bar 1 and the bottom bar 2 are connected with the end bars 3 and 4 by means of elbows 6 and 7, the elbow 6 being designated specifically, owing to functions which it possesses, as will be outlined hereinafter.

The invention includes a striking member or post 8 and a suspension member 9 ordinarily in the form of a post. Projecting 60 from the suspension post 9 are eyes 10 above which are located eyes 11 secured to the end bar 3 of the gate. Through the eyes 10 and 11 passes a pivot element in the form of a rod 12, the lower end of the rod preferably being secured to the lowermost eye 10 on the suspension post 9. Owing to the construction last above outlined, the gate may not only swing horizontally but move 65 vertically as well.

The invention includes a track 15 secured to the suspension post 9. The track at its sides and adjacent its outer end slants downwardly, as shown at 16 and the central portion of the track, opposite to the suspension 70 post 9 is depressed somewhat abruptly to form a loop 17 defining a notch 14 in the upper face of the track, as clearly shown in Fig. 3. The edge of the track 15 is provided with notches 18, 19, 20, 21 and 22, positioned approximately as shown in Fig. 2 and spaced from each other.

Journaled for rotation on the top bar 1 of the gate and restrained against movement in one direction by the elbow 6 is a roller 35 23, restrained against movement in an opposite direction by means of an abutment 24 on the top bar 1, the abutment if desired being held in place by a cross pin 25. Mounted to slide horizontally in the end 90 bars 3 and 4 of the gate frame is a latch 26 in the form of a rod, the latch being adapted at its outer end to engage in a recess 27 formed in the striking post 8, or with any of the common and well known means 95 which, being assembled with the striking post 8, are adapted to receive a latch of the sort hereinbefore described. As indicated at 28, the latch bar 26 is offset so as to clear the filler 5 of the gate frame. Intermediate 100 its ends and relatively near to the end bar 3 of the gate frame, the latch 26 is provided

with an abutment 29. A compression spring 30 bears at one end against the abutment 29, the other end of the compression spring bearing against the end bar 3. Pivoted as shown at 31 to the latch 26 is a locking member in the form of a lever 32 fulcrumed as shown at 33 upon an arm 34 attached to and projecting from the end bar 3, the arm 34 ordinarily being offset as shown at 35 so as to line up the lever 32 with the offset latch 26. The upper end of the lever 32 is adapted to engage in any of the notches 18, 19, 20, 21 and 22.

Let it be supposed that the parts of the structure are disposed as in Fig. 1 of the drawings. Under such circumstances, the latch 26 is thrust to the right by the action of the spring 30, the outer end of the latch coacting with the striking post 8 at 27 as clearly shown in Fig. 2. The upper end of the lever 32 is swung to the left and is engaged in the notch 20. At the same time, the roller 23 rests in the loop 17 of the track 15. Thus, through two instrumentalities, the gate is held in alinement with the striking post 8 and the suspension post 9, it being observed, if for any reason, the latch 26 should fail to engage with the striking post 8, the gate would be prevented from being blown open, by reason of the fact that the roller 23 is lodged in the loop 17 of the track.

In order to open the gate, the latch 26 is pushed to the left until it no longer engages with the striking post 8. By this operation, the spring 30 is put under compression, and the lever 32 is tilted on its fulcrum 33 so that the upper end of the lever no longer is engaged in the notch 20. Thereupon, the gate may be swung to an open position in either direction. When the gate is swung to an open position, the roller 23 rides up along the inclined portions 16 of the track 15 and thus the gate is elevated. The gate may be held in a partially open position by releasing the latch 26 and permitting the lever 32 to swing under the action of the spring 30 until the upper end of the lever is engaged in either of the notches 19 or 21. Similarly, if it is desired to hold the gate in a widely open position, the upper end of the lever 32 may be engaged in either of the notches 22 or 18.

Presupposing that the gate has been opened partially, and that the upper end of the lever 32 is engaged in one of the notches 19 or 21, the gate may be closed by tilting the lever 32 through the medium of the latch 26 so that the upper end of the lever no longer is engaged in the notch. Thereupon the roller 32 will ride down the inclined portion 16 of the track 15 and ultimately come to rest in the loop 17. During this operation, the upper end of the lever 32 under the action of the spring 30 will bear

against the edge of the track 15 and at the appropriate time, the upper end of the lever will snap into the notch or seat 20, the parts being then in the positions shown in Fig. 2.

In Fig. 4 of the drawings, a slight modification of the invention is shown, the operation of the modification being clearly understood from what has been stated hereinbefore in connection with the preferred form of the invention.

Referring to Fig. 4 of the drawings, the gate is denoted generally by the numeral 36, the numeral 37 indicating the suspension post. The means for supporting the gate for pivotal movement and for vertical movement is shown at 38 and the track appears at 39. The numeral 40 designates the gate carried roller and the locking member is shown at 41. The arm which supports the locking member appears at 42 and the numeral 43 indicates the latch. The only difference between the form of invention under discussion and the preferred form resides in the fact that the roller 40 is not journaled on the top bar of the gate but is journaled on a shaft 44 projecting from the end bar 45 of the gate, the track 39 being lowered to coöperate properly with the roller 40.

Having thus described the invention, what is claimed is:—

1. In a device of the class described, a gate; means for mounting the gate for swinging movement and for vertical movement; an inclined track means for supporting the track; gate carried means adapted to traverse the inclined track; a gate carried latch; and a gate carried locking member under the control of the latch and coacting with the track to hold the gate against movement.

2. In a device of the class described, a gate; means for mounting the gate for swinging movement and for vertical movement; an inclined track means for supporting the track; gate carried means adapted to traverse the inclined track; a latch slideable in the gate; and a lever fulcrumed on the gate and pivotally connected with the latch, the track being provided with a seat adapted to receive the lever to hold the gate against movement.

3. In a device of the class described, a gate; means for mounting the gate for swinging movement and for vertical movement; an inclined track; means for supporting the track; gate carried means adapted to traverse the track; a latch slideable in the gate; resilient means for moving the latch; a lever fulcrumed intermediate its ends on the gate; and means for pivotally connecting one end of the lever with the latch; the track embodying means for receiving the other end of the lever.

4. In a device of the class described, a

gate; an inclined track; means for supporting the track; gate carried means adapted to traverse the inclined track; and a manually operable locking mechanism mounted on the gate and coacting with the track to hold the gate in adjusted positions.

In testimony that I claim the foregoing

as my own, I have hereto affixed my signature in the presence of two witnesses.

LEWIS T. JACK.
